UNITED STATES PATENT OFFICE.

LOUIS M. POTTS, OF BALTIMORE, MARYLAND, ASSIGNOR TO AUSTIN McLANAHAN, OF BALTIMORE, MARYLAND.

TELEGRAPHY.

1,135,614.

Specification of Letters Patent. Patented Apr. 13, 1915.

Application filed August 6, 1912. Serial No. 713,558.

To all whom it may concern:

Be it known that I, Louis M. Potts, a citizen of the United States, residing at Baltimore city, State of Maryland, have invented certain new and useful Improvements in Telegraphy, of which the following is a specification.

The primary object of this invention is the providing of a system of telegraphy for operation on lines between a central office and subscribers, though, as will hereinafter more fully appear, my said invention is really not limited to such restricted use.

It is usual in commercial telegraph practice of today to have a looped wire from the central office to a subscriber.

My invention contemplates the utilization of this looped wire to form legs of two simplex lines, one used by the subscriber for sending to central, and the other, by central to send to the subscriber. Such a system, therefore, has the capacity of a one wire duplex line without its disadvantages since, in my system, artificial lines and balanced line relays are not necessary. Moreover, in the present arrangement, it is not necessary to provide synchronizing apparatus at both stations. This apparatus may, for example, be at the central office alone, and the subscriber provided with a line unit which may be driven by a simple electric motor without any synchronizing attachment.

Other advantages of this invention will more readily appear from the following description in which reference will be had to the accompanying drawing which is a diagram illustrating one embodiment of my said invention.

Referring to the accompanying drawing, the parts on the left of the vertical broken line indicate the apparatus and connections at a subscriber's station, for example, while those parts on the right of said line indicate the apparatus at a central office.

In the case shown the apparatus at the subscriber's station includes, among other parts, a line unit comprising a transmitting sunflower consisting of a segmented ring or commutator 1 and a collector ring 2; a receiving sunflower consisting of a segmented ring or commutator 3 and a collector ring 4; brushes 5, 6, 7 and 8 for the respective commutators and collector rings and a direct current motor 9 driving all said brushes.

The brushes 5 and 7 are in permanent elec-

trical connection respectively with brushes 6 and 8 as indicated. Eight segments of the commutator 1 are electrically connected respectively with eight movable contact springs 10, each of which is adapted to move between a pair of stationary contacts 11 and 12, and each pair of these stationary contacts are alternately connected to two conductors 13 and 14, leading from a source of current consisting in the present case, of two direct current dynamos 15 and 16. The positive brush of dynamo 15 is connected to conductor 13, and the negative brush of dynamo 16 is connected to conductor 14, while the other brushes of these two dynamos connect to earth as shown. In this way conductor 13 receives a continuous positive current while conductor 14 receives a continuous negative current. The extra segments of commutator 1, not connected to contacts 10, are alternately connected as shown to conductors 13 and 14.

All the contacts 10 normally engage stationary contacts 12, and since alternate contacts 12 are connected to the same one of the wires 13, 14, an alternating current will be normally delivered to line as the brush 5 sweeps over commutator 1. The manner of operating contacts 10 to transmit the signals constitutes no part of my present invention, so need not here be described in detail. Suffice it to say that these contacts may be operated in any suitable way, either manually as from a keyboard or automatically. In U. S. Patent No. 1105920 granted August 4, 1914, I have described both manual and automatic means which may be employed for operating these contacts.

Eight successive segments of the receiving commutator 3, in the case shown, occupying corresponding angular positions to the eight transmitting segments above referred to and are electrically connected respectively to a coil terminal of each of eight selecting relays 17, the other coil terminals of which relays all connect to a common conductor 18 connected to earth as shown. The extra segments of commutator 3, not connected to relays 17, are all connected to conductor 18. These extra segments may be utilized for various purposes which it is not necessary here to enlarge upon. In the present case it is sufficient to simply show these segments connected to a conductor 18.

The receiving relays 17 may be made to

indicate or record the received signals in any desired way, this operation forming no part of my present invention. In my British patent, above referred to, such receiving 5 relays are employed for the operation of a page printer.

Extending respectively from the collector rings 2 and 4 are two line wires 19 and 20 which lead from the subscriber's station to 10 the central station, and there connect respectively two collector rings 21 and 22 of the central line unit. This latter line unit comprises, in the case shown, a transmitting sunflower consisting of a segmented ring or 15 communicator 23, collector ring 21, and brushes 24 and 25, permanently electrically connected as indicated; a receiving sunflower comprising commutator 26, collector ring 22, and electrically connected brushes 27 and 28; a synchronizing commutator 29, collector ring 30, and electrically connected brushes 31 and 32, and a synchronously driven direct current motor 33 which drives 20 all the brushes 24, 25, 27, 28, 31 and 32 of the central line unit.

The transmitting apparatus at the central station comprises in addition to the sunflower above referred to a series of movable transmitting contacts 34 and stationary contacts 35, 36, electrically connected to conductors 37 and 38, and to the transmitting commutator as described with reference to the transmitting contacts 10, 11 and 12, and conductors 13, 14 at the subscriber's station.

35 The conductors 37, 38 at the central station are in electrical connection respectively with a positive and negative terminal of two direct current dynamos 39, 40 at the central station. The other terminals of 40 these dynamos are connected to earth as described with relation to the dynamos at the subscriber's station.

At the central station the receiving apparatus comprises, as in the case of the subscriber's apparatus, eight selecting relays 41, which are connected to the receiving commutator 26 as described with relation to the relays 17 at the subscriber's station, and the coils of all these relays 41 are connected to a common conductor 42, which connects to the odd segments of commutator 26 and to earth as described with relation to conductor 18, except in the case of the conductor 42 there is included in its circuit between the last of the relays 41 and earth, the coils of a synchronizing relay 43. Alternate segments of the synchronizing commutator 29 are connected respectively to the tongue contacts 44 and 45 of this 55 relay, while the tongue of said relay is permanently connected to a conductor 46 which leads to one of the brushes of motor 33, the latter motor receiving its driving current from D. C. mains 47 and 48.

60 Tapped at one side to wire 46 and at the

other to D. C. mains 47, is the synchronizing resistance 49 which is utilized to regulate the speed of motor 33 as hereinafter described.

The means here shown for regulating the 70 motor 33 to synchronism with the motor 9, said means including relay 43, the synchronizing sunflower and resistance 49, and electrical connections of these parts, except as to the connection of relay 43 to the commutator 26, is substantially the same shown 75 and described in U. S. Patent No. 726,750, granted to me April 28, 1903, and while not herein claimed will be briefly described in order that the parts shown may be more 80 readily understood.

The tongue of relay 43 is kept in constant vibration between contacts 44 and 45 by an alternating current received from dynamos 15, 16 through conductors 13, 14, contacts 10, commutator 1, collector ring 2, line 19, collector ring 22, receiving commutator 26, relays 41 and conductor 42, assuming that both motors 9 and 33 are operating. Now, if the tongue of relay 43 85 is against either of its contacts 44, 45, while brush 31 is passing over any of the segments of the commutator 29 connected to the relay contact with which the tongue is at that time engaging, it will be seen that the resistance 49 will be short circuited; while if the said relay tongue is engaging either of said contacts at the same time that the brush 31 is passing over any of the segments 90 of commutator 29 connected to the opposite relay contact, that is, the one which the tongue is not at that time engaging, the resistance 49 will be in series with the armature of motor 33. In one case the motor will receive much greater current than in the 95 other. Consider any case in which the vibrations of the relay tongue and rotation of the brush have some relation between the 100 above two. If any relation between the first two mentioned is continuously maintained, it will be readily seen that at rapidly recurring intervals the resistance 49 will be 105 in circuit and out of circuit with the motor 33. Depending upon the relation between the vibration of the relay tongue and the 110 rotation of said brush, the intervals during which this resistance is in circuit and out of circuit with the motor armature will vary in length, and in addition to the regular current flowing through the motor armature, there will be a pulsating current flowing 115 through the same, and the strength of these impulses will depend upon the relation existing between the vibrations of the tongue of the relay 43 and the rotation of 120 the brush 31, consequently, while the relay tongue is vibrating in unison with the rotation of said brush, there can be various amounts of current flowing through the 125 armature of the motor, depending upon the 130

relation of the tongue of relay 43, to the brush 31 which is hereafter spoken of as the phase difference. If the rate of vibration of the relay tongue increases, the phase relation between the vibration of said relay tongue and the rotation of the brush arm will change, but in such a manner as to strengthen the impulses flowing through the motor armature, and, consequently, the speed of the motor will be increased, but only until this speed corresponds to the rate of vibration of the relay tongue. If the armature of the motor attempts to go faster than the vibration of the relay tongue, the impulses through the armature are weakened and the speed is still kept normal. Consequently the speed of the motor follows any changes in the vibrations of the relay tongue and any tendency for the motor to change its speed, as, for instance, a change in the voltage in the power circuit, is immediately compensated for by a slight shift in the phase difference above mentioned.

Since the frequency of the alternations of the current delivered to relay 43 is determined by the speed of motor 9, it will be seen that the motor at the subscriber's station sets the pace and need not have any means for regulating its speed to synchronism. While these motors in practice of course run at the same speed, motor 33 is actually designed to run at a higher speed than motor 9. For example, motor 33 has been designed to run at 2200, and motor 9 at 1500 revolutions per minute on a 110 volt circuit. This is necessary to allow for the decrease in the speed of motor 33 by its regulating resistance.

Signals may be transmitted from the subscriber to central by operating the contacts 10 so as to bring these contacts in various combinations into engagement with contacts 11, thereby sending to line impulses of opposite polarity from normal. The receiving relays 41 at central are so wound that the normal impulses passing through their coils operate all these relays so as to send their tongues against their back stops. Therefore, when a given combination of contacts 10 are operated to transmit to line a corresponding combination of impulses of opposite polarity from normal these impulses will be received by corresponding relays 41, which will thereby be caused to send their tongues against their forward contacts and thus operate the desired receiving apparatus. In a similar way signals are transmitted to the relays 17 of the subscriber from the transmitting contacts at the central station.

It will, therefore, be seen that it is important that the sunflower brushes at the two stations be driven accurately in synchronism. It will be observed, however, that while there are two sources of signaling current,

one at each of the stations, but one of these sources is utilized for effecting the synchronism and this source is at the subscriber's station.

It will also be seen that while there are two lines and two sources of signaling current, one individual to each of said lines, the timing of the transmission to line of all the impulses, that is, the frequency and duration of all the impulses is governed by the transmitting sunflower at one station only, in the case shown, the subscriber's station.

I do not, however, wish to be understood as limiting my invention to any one specific way of synchronizing the motor 33, since this may be done in other ways than that shown.

The reversed signal impulses do not interfere with the synchronism so long as their number is less than fifty per cent of the total number of impulses received by relay 43. As long as this proportion is maintained the synchronism will be amply maintained during the reversals by the inertia of the moving parts.

The extra segments in the commutators 1, 3, 23 and 26, hereinafter referred to, may be used for various purposes which it is not necessary to describe. In the drawing they are simply shown connected to prevent a gap in the current transmitted to line. Also, means may be provided for automatically causing the brushes of the receiving commutators to adjust themselves to angular positions corresponding to their respective transmitting brushes so as to arrive simultaneously on corresponding segments with the latter brushes. This, however, while an important matter in the practical operation of the system is not claimed as a part of the present invention so need not be here described. One way of accomplishing this is shown and described in U. S. Patent No. 713,497, granted November 11, 1902, in the Rowland System.

Various modifications of the specific embodiment of my invention may be made without departing from the spirit thereof, but—

What I claim is:

1. An electric telegraph, comprising two separate transmission lines connecting two stations, a separate source of signaling current for each of said lines, transmitting and receiving apparatus for each of said lines, the transmitting apparatus of each of said lines comprising mechanism to time the transmission of impulses to said lines from said sources, and means at one of said stations governing the speed of operation of the impulse timing apparatus at both stations.

2. An electric telegraph, comprising two separate transmission lines connecting two

stations, a separate source of signaling current for each of said lines, a transmitting and a receiving sunflower for each of said lines, means common to both the transmitting and receiving sunflowers at one station to drive the same, and common driving means for the transmitting and receiving sunflowers at the other station on said lines, the driving means for the sunflowers at one station setting the pace and timing the duration of the impulses transmitted to line at both stations.

3. An electric telegraph, comprising transmitting and receiving sunflowers at each of two stations, two separate lines connecting respectively the transmitting sunflowers at said stations with the receiving sunflowers at the distant stations, an independent source of signaling current at each of said stations from which impulses are transmitted to said lines respectively through the transmitting sunflowers connected thereto, and means at each of said stations common to both sunflowers at said stations for driving the same.

4. An electric telegraph comprising transmitting and receiving sunflowers at each of two stations, two separate lines connecting respectively the transmitting sunflowers at said stations with the receiving sunflowers at the distant station, an independent source of signaling current at each of said stations from which impulses are transmitted to said lines respectively through the transmitting

sunflowers connected thereto, and means at each of said stations for driving the same, means at one of said stations to set the pace for all said sunflowers, and means at the other of said stations to regulate the speed of the sunflowers at that station to synchronization with the sunflowers at the other station.

5. An electric telegraph comprising transmitting and receiving sunflowers at each of two stations, two separate lines connecting respectively the transmitting sunflowers at each of said stations to the receiving sunflowers at the distant station, an independent source of signaling current at each of said stations from which impulses are transmitted to said lines respectively through the transmitting sunflowers connected thereto, an electric motor at one of said stations driving both the transmitting and receiving sunflowers at that station, an electric motor at the other of said stations driving both said sunflowers at that station, and means at the latter station governed by the signaling current from the distant station to regulate the speed of the second named motor to synchronization with that of the first named motor.

In testimony whereof I affix my signature in presence of two witnesses.
